UNITED STATES PATENT OFFICE.

DOMINICK A. REAGAN, OF ALTOONA, PENNSYLVANIA.

SAND-PIPE FOR LOCOMOTIVES.

SPECIFICATION forming part of Letters Patent No. 367,062, dated July 26, 1887.

Application filed January 26, 1887. Serial No. 225,512. (No model.)

To all whom it may concern:

Be it known that I, DOMINICK A. REAGAN, of Altoona, Blair county, State of Pennsylvania, have invented a new and useful Improvement 5 in Sand-Pipes for Locomotives, of which the following is a true and exact description, due reference being had to the accompanying drawings, which form a part hereof.

The object of my invention is to provide locomotive-engines with sand-pipes which shall be free from the tendency to choke or become clogged, which sometimes impairs the usefulness of those now in use.

I have discovered that the choking of the 15 sand-pipe is usually due to the presence of water about the mouth of the pipe, a little water at the edge causing some sand to stick there when the pipe is used and when the water is constantly present, as on a rainy day.

20 More sand will lodge about the mouth of the pipe when it is used again, until finally the pipe is entirely choked and filled with sand, which I have found will become wet all the way back to the sand-box, even wetting the 25 sand in the box itself. To overcome this difficulty I have devised a shield to shed water from the pipe and prevent it from reaching the mouth thereof at least sufficiently to avoid much of the trouble.

30 Reference is now had to the drawings, which illustrate my invention, and in which Figure 1 is a side view of a portion of a locomotive, showing the sand box and pipe in their usual position; Fig. 2, an enlarged sectional view 35 of the end of the sand-pipe provided with my improvement; and Figs. 3, 4, and 5 are views of a number of modifications of my invention.

A is the sand-pipe; B, the sand-box; C, an engine driving wheel; D D' D² D³, my 40 proved shields or water-deflectors.

E is the railway-track; F, Figs. 2 and 3, the mouth of the sand-pipe, (shown as projecting into the bell-like shields D and D').

f, Fig. 2, is a thread on the sand-pipe to enable the bell D to be screwed into place.

d is a gutter formed in the upper forward part of the bell D, and adapted to catch any water flowing onto this part of the bell and deflect it to the lower edge, d'.

50 e e', Figs. 3, 4, and 5, show the mouth of the bell as having a recurved edge tapering gradually to a point at the bottom, e', this construc-

tion being especially desirable when the pipe A does not project into the bell. (See, for instance, Fig. 4.)

G is a deflector-plate covering the front of the shield or bell D, Fig. 5, its object being to prevent water from splashing into the sand-pipe from the track or road-bed.

The operation of my improvement is of course apparent, the shields deflecting and shedding the water away from contact with the mouth of the sand-pipe, and being, besides, so large at their mouths and so shaped that no large amount of sand would be able to collect in them and clog the action of the sand-pipe. The shields or bell-mouths may be made of cast metal, as in Fig. 2, or of sheet metal, as indicated in Figs. 3, 4, and 5, and may be secured in any convenient manner. 70 They are of course capable of many modifications in shape and adjustment, the figures illustrating those forms which I believe will be found most efficient in practice.

Having now described my invention, what I 75 claim as new, and desire to secure by Letters Patent, is—

1. In combination with the sand-pipe of a locomotive, a bell-mouth secured thereto and having its edges curved or grooved, as specified, so as to deflect the water flowing onto it toward its bottom point.

2. In combination with the sand-pipe of a locomotive, a bell-mouth secured thereto and projecting over but not coming in contact with 85 the mouth of the sand-pipe, substantially as and for the purpose specified.

3. In combination with the sand-pipe of a locomotive, a bell-mouth secured thereto, and a supplemental shield extending in front of 90 the bell mouth, as specified, to prevent water from splashing into the sand-pipe.

4. In combination with the sand-pipe of a locomotive, a bell-mouth secured thereto, projecting over but not touching the mouth of 95 the sand-pipe, and having its edges curved or grooved to form a gutter and direct the water to the lowest edge, substantially as and for the purpose specified.

DOMINICK A. REAGAN.
